US0D1015669S

(12) **United States Design Patent** (10) **Patent No.:** **US D1,015,669 S**
(45) **Date of Patent:** **** Feb. 20, 2024**

(54) **CONTAINER RING**

(71) Applicant: **BWAY CORPORATION**, Atlanta, GA (US)

(72) Inventors: **Frano Luburic**, Costa Mesa, CA (US); **John Homan**, Naperville, IL (US)

(73) Assignee: **BWAY Corporation**, Atlanta, GA (US)

(**) Term: **15 Years**

(21) Appl. No.: **29/789,610**

(22) Filed: **Oct. 4, 2021**

Related U.S. Application Data

(63) Continuation-in-part of application No. 17/288,015, filed on Apr. 23, 2021, and a continuation-in-part of application No. 17/288,017, filed on Apr. 23, 2021, and a continuation-in-part of application No. 29/725,734, filed on Feb. 26, 2020, now Pat. No. Des. 932,721, and a continuation-in-part of application No. 29/725,733, filed on Feb. 26, 2020, now Pat. No. Des. 933,324.

(57) **CLAIM**

The ornamental design for the container ring, as shown and described.

DESCRIPTION

FIG. 1 is a perspective view of a container ring;
FIG. 2 is a perspective view of a container ring;
FIG. 3 is a top view of a container ring;
FIG. 4 is a bottom view of a container ring;
FIG. 5 is a side view of a container ring; and,
FIG. 6 is an enlarged partial cross-sectional view of a container ring taken from line 6-6 in FIG. 3.

1 Claim, 6 Drawing Sheets
